UNITED STATES PATENT OFFICE

119,681

DESIGN FOR A TEXTILE FABRIC

Samuel S. Shapiro, New York, N. Y.

Application February 12, 1940, Serial No. 90,211

Term of patent 3½ years

To all whom it may concern:

Be it known that I, Samuel S. Shapiro, a citizen of the United States of America, residing in the city of New York, county of New York, and State of New York, have invented a new, original, and ornamental Design for a Textile Fabric, of which the following is a specification, reference being had to the accompanying drawing, forming part thereof.

The figure on the drawing is a plan view of a textile fabric showing my new design, which is repeated lengthwise between the selvage edges of the fabric as shown.

I claim:

The ornamental design for a textile fabric, substantially as shown and described.

SAMUEL S. SHAPIRO.
